Inventor

G. P. MC Sweeney

Plamme & Sweeney

Attorney

UNITED STATES PATENT OFFICE.

GEORGE P. MCSWEENEY, OF MEMPHIS, TENNESSEE.

DUST COLLECTOR.

Application filed May 5, 1925. Serial No. 28,152.

To all whom it may concern:

Be it known that I, GEORGE P. MCSWEENEY, a citizen of the United States, residing at Memphis, in the county of Shelby 5 and State of Tennessee, have invented certain new and useful Improvements in Dust Collectors, of which the following is a specification.

This invention has reference to an improved dust collector and the principal object is to generally improve upon devices of this class, by providing one of comparative simplicity and durability, the construction being such that it is exceedingly practical 10 in operation, and inexpensive to both the manufacturer and the user.

The primary structural feature of the present invention is the provision of a plurality of internal radially spaced cones of truncated form, which are arranged in a manner to more effectively separate the dust particles from the air, whereby to free the air of dust in a manner more easy and efficient than has heretofore been contemplated. 20

The particular details for accomplishing this result will become apparent from the following description and drawing.

In the accompanying drawing, forming a part of this application, and in which like numerals are employed to designate like parts throughout the same:

Figure 1 is a central vertical section through a dust collector constructed in accordance with the present invention.

Figure 2 is a top plan view of the same.

Referring to the drawing in detail, the reference character 1 designates an outer casing, which is provided with an upper cylindrical portion 2 and a reduced portion 3, which serves to concentrate and cause the dust particles to gravitate downwardly into the outlet pipe 4. An opening is formed in one side of the upper cylindrical portion and an air intake 5 connects the disc to conduct air into the separator. As before indicated, the distinction of the invention is the provision of a plurality of supplemental and internal cones 6, 7 and 8. It will be noted 45 that the apices of these cones are truncated,

and that the cones are graduated in size from the smaller inner cone 6 to the outer larger cone 8. They are thus disposed in concentric radially spaced relation and terminate on vertically spaced planes. A tortuous air passage is thus provided, which serves to completely separate the dust particles from the air, causing them to gravitate downwardly, into the restricted lower portion 3 of the casing. Connected to the top of the casing are appropriate air outlets 9. In practice, there may be any desired number of these outlets to retard or accelerate the discharge of air as desired. It will also be noted that an opening 10 is 55 provided at the top of the device, to facilitate the circulation of air. Furthermore, a plurality of legs 11 are connected to the larger outer cone 8 and depend therefrom and serve to support a disk 12. The disk is 60 disposed at a point to provide a comparatively restricted annular discharge space 13, between its periphery and the inner surface of the wall of the casing. 65

From the foregoing description, it is obvious that the inflowing air enters the casing, through the intake pipe 5, follows a tortuous path compelled by the presence of the supplemental cones 6 to 8, and escapes through the outlet 10. During its passage 70 through the device, the particles of dust are separated therefrom, and gravitate downwardly into the casing and are discharged through the pipe 4, which leads to any appropriate place of deposit. Undoubtedly, 75 persons familiar with devices of this kind will be able to obtain a clear understanding of the same, after considering the description, in connection with the drawing. Therefore, a more lengthy description of 80 the same is probably unnecessary.

While the preferred embodiment of the invention has been shown and described, it is to be understood that minor changes coming within the field of invention claimed 85 may be resorted to, if desired.

I claim:

A dust collector comprising a casing having an upper cylindrical portion and a reduced and tapered lower portion terminat- 90 100

ing in a dust discharge, an air supply pipe connected with said cylindrical portion, a plurality of internal separating cones disposed in said casing, said cones having their apices truncated and being of varying lengths, legs connected to and depending from the outermost internal cone, and a disk

supported on the lower ends of said legs and having its peripheral edge spaced from the adjacent wall of said casing.

10

In testimony whereof I affix my signature.

GEORGE P. McSWEENEY.
